UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP BEAM FOR LOOMS.

Application filed September 27, 1926. Serial No. 137,860.

This invention relates to improvements in warp beams for looms and it is the principal object of the invention to provide a quickly adjustable false head for the barrel of the 5 beam to vary the width of the warp space.

In my co-pending application Ser. No. 86,066 there is shown a warp beam formed of a steel tubular barrel having square threads cut thereon to receive internal square 10 threads cut on the hub of the false head to permit longitudinal adjustment of the head along the beam. It is an important object of my present invention to improve upon the adjusting feature of the beam by providing 15 the barrel shown herein with helical grooves of very coarse pitch to cooperate with projecting screws extending from the smooth bore of the false head into the grooves to afford a very quick adjustment.

20 In said application I have shown relatively large holes to receive the knotted ends of the warp threads which have been tied together and it is a further object of my invention to provide an improved means for 25 holding the warp ends comprising a flexible member stretched longitudinally inside the tube and having the warp ends tied thereto and accessible through small openings in the barrel.

30 It is a further object of my invention to provide an improved holding device to secure the false head in adjusted position, said device comprising shoes or pads mounted in recesses formed in the hubs of the false 35 heads and being of sufficient length to overlap the aforesaid holes which afford access to the flexible holding member.

With these and other objects in view which will appear as the description proceeds, my invention resides in the combination and arrangement of parts hereinafter described and set forth in the claims.

40 In the accompanying drawings wherein I have shown a convenient embodiment of my invention,

Fig. 1 is a side elevation of a loom warp beam made according to my present invention,

Fig. 2 is an enlarged transverse vertical cross section on line 2-2 of Fig. 1,

50 Figs. 3 and 4 are sections on lines 3-3 and 4-4, respectively, of Fig. 2,

Fig. 5 is a fragmentary enlarged vertical transverse section on line 5-5 of Fig. 1

showing the manner of securing the warp 55 ends to the beam below the periphery of the barrel,

Fig. 6 is a section on line 6-6 of Fig. 5 and extending along a portion of the beam 60 to indicate how the flexible member acts in holding the warp ends tied thereto,

Fig. 7 is a fragmentary vertical section of the warp beam on line 7-7 of Fig. 6, with certain of the parts in a different position, 65 and

Fig. 8 is a detail vertical section through the holding shoe or pad and showing the relation of the same with respect to one of the holes adjacent thereto through which the 70 warp ends extend.

Referring to the drawings it will be seen that I have provided a barrel 10 of steel tubing and have secured thereto in any approved manner friction heads 11 from which extend gudgeons 12 by means of which the beam may be supported in a loom. The friction heads 11 are for the purpose of receiving flexible bands or straps which constitute part of the let-off motion (not 75 shown) of the loom.

In carrying my invention into effect I provide each end of the beam with compound spiral grooves, two being shown at 20 and 21, respectively. The space between the grooves forming the surface of the beam is 80 considerably longer than the width of the grooves. I further provide a pair of false heads 22 each of which has a hub 23 with a substantially smooth bore 24 as shown particularly in Figs. 3 and 4. Said hubs have 85 extending therethrough on opposite sides thereof guide studs or screws 25 the inner ends of which are formed preferably cylindrical as at 26 and are received in the grooves 20 and 21 so as to afford means by 90 which the false heads may be moved toward and from the drums 11. In order to secure the false head in any adjusted position the hub is provided with a pair of recesses 27 shown particularly in Figs. 2 and 4 into 95 each of which extends a stud 28 threaded into the hub and having a ball end 29 passing into and having holding connection with the outer part of a shoe 30. Each shoe is 100 of substantial length as shown in Figs. 2 and 8 and has the inner surface thereof concave so as to fit snugly with the outer cylindrical surface of the barrel. By tightening

or loosening the screws 28 the shoes 30 may be clamped in place to hold the adjustment of the false head or to permit adjustment of the false heads along the barrel.

5 When a new warp is being placed on the beam the ends are divided into small groups which are tied in one way or another to the warp beam so that as the latter is rotated by power the warps will be drawn from a 10 creel. In my present invention I provide for stringing the different groups of threads onto a flexible member such as a cord or small rope, this feature of the invention being shown particularly in Figs. 5, 6, and 15 7, where it will be seen that I have secured a comparatively small wooden strip 31 on the interior of the barrel 10 by wood screws 32 which lie below the outer surface of the barrel and have extended said strip longitudinally 20 along the barrel as indicated in Fig. 6. Adjacent said strip I have provided a plurality of holes 33 which extend through the wall of the barrel and are so placed that the adjacent edge of the wooden strip 31 25 projects slightly beyond the near sides of the holes as shown in Fig. 7.

A plurality of screw eyes 34 are secured to the strip 31 and are located as shown in Fig. 6 intermediate the holes 33. There is 30 threaded through said eyes a cord 35 the portions of which lying intermediate the eyes 34 are accessible through the openings 33 by means of a convenient tool such as a hook 36 shown in Figs. 6 and 7. Said cord 35 may be secured at both ends thereof to the wooden strip by having knots formed thereon to engage the endmost screw eyes 34 as indicated in Fig. 6.

When a new warp is to be tied to the beam 40 the false heads 22 will be moved as previously described to positions defining the correct space for the warp and clamped in position by the screws 28 and shoes 30. The warps will then be divided into small groups 45 and the hook 36 passed into the hole nearest one of the false heads to engage and withdraw the cord 35 to a position similar to that shown in Fig. 7. One of the endmost small groups of warp threads is then tied to the projecting part of the cord and the hook 50 is then inserted through the next hole to lift another part of the cord 35 through said next hole after which the next small group of warps will be tied thereto. This procedure is followed until all the warps are 55 tied to the cord. It is to be understood that the rope 35 is somewhat longer than the distance between the end eyes so that it will be possible by taking up the slack in the rope 60 to have a portion thereof extend upwardly through one or another of the holes 33 as shown in Fig. 7. The warp beam may then be set in rotation to turn in either direction to wind the warp on the beam from the creel 65 (not shown). Any unevenness which may

have resulted in the tying in of the warp ends will adjust itself because of the flexibility of the cord 35. For instance, as shown in Fig. 6 one group indicated at W^a 70 may be relatively tight so as to use up a comparatively long length of the slack of the rope, whereas the group W^b next thereto may be relatively long and require less slack. In this way the flexibility of the cord 35 tends to distribute the pressure on all the 75 groups of warps and accommodate any unevenness in the tension of the various groups. Should the cord 35 become broken one of the friction heads 11 may be removed by loosening screw 37, (Fig. 1) and a new 80 cord threaded through the eyes.

From the foregoing it will be seen that I have provided a warp beam for looms wherein the barrel is formed of metal tubing having spiral grooves of coarse gauge cut 85 therein to receive the studs 25 of the false heads so that the warp when wound on the barrel will be affected little if any by the grooves. Also, the internal bore of the false heads is smooth and free from screw threads. It will further be seen that the shoes are longer than the diameter of the holes 33 so as to bridge the latter and be always in contact with some portion of the 90 surface of the barrel, so that the beam can be locked in any position irrespective of the position of the openings 33 with respect to the shoe. Also, it will be seen that I have provided a flexible rope or cord located 95 inside the beam and accessible through openings in the latter, the cord being provided with a small amount of slack by means of which a portion thereof may be drawn out of the beam for the purpose of tying the 100 warp sections thereto. Also, this slackness 105 of the cord acts to compensate for any unevenness in the length or tension of the various groups of warp threads. Another 110 feature of the invention is that the wooden strip 31, in being disposed so as to extend slightly beyond the adjacent edges of the holes 33, acts as a guard to hold the cord 35 and warps W away from the inner edges of the openings 33 which are likely to have a 115 slight burr due to the drilling operation.

Having thus described my invention it will be apparent that changes and modifications may be made therein by those skilled in the art without departing from the spirit and scope of the invention, and I do not wish to be limited to the details herein disclosed but what I claim is:

1. In a hollow warp beam for looms, a tubular barrel having openings therein through which the warp threads may extend, and a flexible member extending along the interior of the barrel to have warp threads tied thereto at a plurality of points.
2. In a hollow warp beam for looms, a tubular barrel having openings therein

through which the warp threads may be passed, a flexible member extending longitudinally within the barrel, and a plurality of devices in the interior of the barrel to 5 guide the flexible member to limit movement thereof, said flexible member being accessible through the aforesaid openings in the barrel for the purpose of having the warp threads tied thereto.

10 3. In a hollow warp beam for looms, a tubular barrel having openings therethrough through which the warp threads may be passed, a flexible member extending along the interior of the barrel, means to 15 hold the ends of the flexible member so that the latter is slack, and a plurality of devices each located between adjacent openings in the barrel to restrain movement of the flexible member, the warp threads extending 20 through the openings and being secured to the flexible member, whereby any unevenness resulting in the tying of the threads to the flexible member will be compensated for by taking up sufficient slack of said member 25 to adjust said unevenness of tension.

4. In a hollow warp beam for looms, a tubular barrel having a series of openings therethrough, a longitudinally extending member secured to the interior of the barrel 30 and having a portion thereof provided with a smooth surface extending beyond the edges of said openings toward the centers of said openings, and a flexible element extending along said member to have the warp tied 35 thereto and guided at a plurality of points, said smooth portion of the member guarding said flexible member and the warp threads tied thereto to hold the same away from the adjacent edges of the openings in the barrel.

40 5. In a hollow warp beam for looms, a tubular barrel, and a flexible slack member confined within the barrel and having the ends thereof limited in movement, the warp

threads extending through the barrel and being secured to the flexible member. 45

6. In a hollow warp beam for looms, a tubular barrel, and a flexible slack member confined within the barrel and having the ends thereof limited in movement, the warp threads extending through the barrel and 50 being secured to the flexible member at a plurality of points in relatively small groups.

7. In a hollow warp beam for looms, a tubular barrel, a flexible slack member confined within the barrel and having the ends thereof limited in movement, the warp threads extending through the barrel and being secured to the flexible member, and removable friction heads held to the barrel, 60 said heads being removable to afford access for replacement of the flexible member.

8. In a hollow warp beam for looms, a tubular barrel, a plurality of aligned hollow devices located on the interior of the barrel, and a slack flexible member extending through said devices, the warp threads extending through the tubular barrel and being tied to the flexible member in small groups 65 at points intermediate the devices. 70

9. In a hollow warp beam for looms, a tubular barrel, a plurality of aligned hollow devices located on the interior of the barrel, a slack flexible member extending through said devices, the warp threads extending through the tubular barrel and being tied to the flexible member in small groups 75 at points intermediate the devices, and friction heads at the end of the barrel, one of said heads being removable to afford 80 access to the hollow devices so that the flexible member may be threaded therethrough.

In testimony whereof I have hereunto affixed my signature.

ALBERT A. GORDON.
